PAGE 2

FIG. 3

FIG. 4

Fig. 5

FIG. 1 is a view in perspective of a pneumatic tire spreader showing my new design;

FIG. 2 is a view in top plan;

FIG. 3 is a view in front elevation;

FIG. 4 is a view in rear elevation; and

FIG. 5 is a view in side elevation showing the side opposite to that shown in FIG. 1 or as seen from left to right with respect to FIG. 3.

The characteristic features of my design for the pneumatic tire spreader disclosed reside in the hood-like motor housing and particular support associated therewith as shown.

I claim:

The ornamental design for a pneumatic tire spreader, as shown and described.
